UNITED STATES PATENT OFFICE.

YOSHIKAZU OKAMIYA, OF NEW YORK, N. Y.

LADDER.

1,109,357.

Specification of Letters Patent. Patented Sept. 1, 1914.

Application filed December 1, 1911. Serial No. 663,193.

To all whom it may concern:

Be it known that I, YOSHIKAZU OKAMIYA, a subject of the Emperor of Japan, and resident of the borough of Manhattan, city, 5 county, and State of New York, have invented certain new and useful Improvements in Ladders, of which the following is a specification.

This device although intended as an improvement in step ladders, or ladders intended for household use is so important that ladders for general use if constructed with these improvements will be found very desirable.

15 Although of light construction and although more portable than the ordinary ladder because of its peculiar shape, my ladder does not sacrifice any of the stability or usefulness found in the more common ladders, in fact the efficiency is added 20 to, because of the ease with which the device may be changed from one place to another, its stability while resting on an uneven surface and the quickly detachable 25 back brace, which is intended to support the ladder at mid-height. These and other 30 advantages as well as the means for obtaining them will be set forth as the specification progresses.

35 The following is what I consider the best means of carrying out this invention.

The accompanying drawings form a part 40 of this specification, in which:

Figure 1 shows my device in a closed condition. Fig. 2 shows the device open, and 45 the figure discloses the means for connecting the cross-bars or rungs, also the depth of the groove. Fig. 3 shows a portion of one of the side rails, this figure is 50 in side elevation and shows the width of the groove. Fig. 4 shows the back brace closed. Fig. 5 shows a ladder supported by the back brace and, Fig. 6 shows the back brace open ready to be applied. Fig. 55 7 shows in elevation and on a smaller scale a modified form of back brace in which the lower end of the legs are spread.

Similar reference numerals indicate like 60 parts in all the figures where they appear.

55 In describing my invention, I will first describe the ladder proper and particularly as it is shown in Figs. 1, 2, and 3, and will later describe the means for supporting it, the means which is shown in Figs. 4, 5, and 6.

At 1, and 2 I have shown the side rails

of a ladder each of which is intended to have its lower end rest upon the ground or any other firm support, and have its mid-length steadied and supported by means 60 to be later described. The top may rest against a wall, ledge, or coping like an ordinary ladder, if the upper half of the ladder is to be used.

At the lower end of the bar 1, I have cut 65 away a portion of the inner end of the bar so as to produce the angle 3, and at the upper end of the bar 1, I have added a block 4 equal in width and thickness to the bar 2 and I have beveled the lower end of this 70 block 4. The upper end of the bar 2 is beveled at 5, and a block 6 beveled at 7 is secured to the lower end of this bar. The bolts 8 and pins 9 secure the blocks 4 and 6 in position, and I have so proportioned 75 the parts and the lengths of the blocks 4 and 6, that when the ladder is closed as is shown in Fig. 1 the angled or beveled end 3 of the bar 1 will rest upon the surface 7, and the beveled upper end 5 of the bar 2 80 will support the beveled lower end of the block 4. In this way, when the ladder is closed it presents the appearance of two straight and smooth bars of a length slightly longer than the length of either of 85 the bars 1 or 2. Each of the bars 1 and 2 is provided with a longitudinal groove 10, and a series of transverse holes, spaced equal distances apart are produced in the walls of the grooves 10.

90 I provide a plurality of rungs, which may be flat for their full length, and which should be of a thickness equal to the width of the groove 10. Each of these rungs 11 has its ends rounded, and each is provided 95 with a perforation adjacent to each rounded end. A pin 12 passes through the holes in the side walls of the grooves 10, and through the perforation in one end of the rung 11, securing the rung in pivotal connection with the side bars 1 and 2.

I have before mentioned that I provide a plurality of the rungs 11, and each is connected in a manner exactly similar to that already described. In this way I produce a 105 ladder foldable in a manner sometimes called a single caglate fold. The pins 11, of which I provide two for each rung 11 may be of wood, but I prefer that metal pins or bolts be used so that, should a rung 110 warp or break a new perfect one may be substituted therefor. The brace or support

is also provided with two uprights or bars 12, and 13, but it is not my intention to groove these bars. I have connected the bars 12 and 13 together by means of two cross-pieces 14 and 15, which are joined to the bars 12 and 13 by means of the bolts 16, which also serve as pivots. This back-brace may also fold as is shown in Fig. 4, though I have taken no pains to make the sides 10 when folded, a smooth continuous piece.

To the outside; though at the upper end of each of the bars 12 and 13 I have secured a metallic Y or crotch member 17, and at about mid-height of each of the bars 12, and 15 12 I have pivotally connected a rigid though foldable metallic brace 18. This brace 18 is formed in four parts all hingedly connected in series for a purpose that will appear later.

20 In operation the ladder is unfolded by an outward pull on the bar 1, while the lower end of the bar 2 is resting on a floor or other support. When the lower end of the bar 1 is also resting upon the supporting surface 25 the brace or support may be attached, by first being unfolded and then having its metallic Y or crotch members engage with the screws or studs 19 and 20. When the ladder is erected and assumes the desirable 30 angle, one of the notches 21, in the brace 18 may be engaged upon the screws 22, and should one or more sections of the brace 18 extend beyond and be not supported by a screw 22, they will turn upon the hinge 23

into a vertical position out of the way of the 35 operator.

It is obvious that a rigid or flexible brace may be used as a substitute for the notched and hinged member 18, and it is obvious that the bars 12 and 13 of the support may be 40 grooved and the cross pieces pivoted within the groove. Other modifications may be made by a good mechanic without departing from the principle or sacrificing the advantages of this invention.

45

Having carefully and fully described my invention what I claim and desire by Letters Patent is:—

The combination with a folding ladder of a foldable prop therefor comprising a plurality of longitudinal members 12 and 13 each pivotally connected to cross bars 14 and 15 and one of said pivots being 50 slideable in one of said cross bars, a Y shaped engaging member at one end of each said longitudinal member, and a serrated member pivoted at approximately mid-length of each said longitudinal member said serrated members being sectionally foldable as and for the purpose set forth.

55

Signed at New York city N. Y. this 15 day of Nov. 1911, in the presence of two witnesses.

YOSHIKAZU OKAMIYA.
